CLAIM

The ornamental design for a line protector distribution board for telephone exchange systems, as shown and described.

DESCRIPTION

FIG. 1 is a perspective view of a line protector distribution board for telephone exchange systems;
FIG. 2 is a front elevational view thereof;
FIG. 3 is a rear elevational view thereof;
FIG. 4 is a top plan view thereof;
FIG. 5 is a bottom plan view thereof;
FIG. 6 is a left side elevational view thereof; and,
FIG. 7 is a right side elevational view thereof.

FIG. 1

FIG. 4

FIG. 2

FIG. 5

FIG. 3

FIG. 7

FIG. 6
